[57] **CLAIM**

The ornamental design for a folding pole stretcher, as shown and described.

DESCRIPTION

FIG. 1 is a front elevational view of a folding pole stretcher showing our new design;

FIG. 2 is a top plan view thereof;

FIG. 3 is a side elevational view thereof, the opposite side view being a mirror image of that shown;

FIG. 4 is a top perspective view thereof;

FIG. 5 is a bottom perspective view thereof; and

FIG. 6 is a perspective view thereof in a folded configuration.
